UNITED STATES PATENT OFFICE.

JOHN B. TURBEVILLE, OF CLEBURNE, TEXAS.

COOK-STOVE.

1,010,536.

Specification of Letters Patent.

Patented Dec. 5, 1911.

Application filed May 1, 1911. Serial No. 624,361.

To all whom it may concern:

Be it known that I, JOHN B. TURBEVILLE, a citizen of the United States, residing at Cleburne, in the county of Johnson and State of Texas, have invented a new and useful Cook-Stove, of which the following is a specification.

It is the object of the present invention to provide a cooking stove, having superposed ovens, either of which may be used at will, and to provide heating means and controlling means, the controlling means serving to cut out one of the ovens, at the will of the operator.

15 A further object of the invention is to improve generally, the construction of cook stoves, and to provide novel means for controlling the circulation of the products of combustion therethrough.

20 With the foregoing and other objects in view which will appear as the description proceeds, the invention resides in the combination and arrangement of parts and in the details of construction hereinafter described

25 and claimed, it being understood that changes in the precise embodiment of invention herein disclosed can be made within the scope of what is claimed without departing from the spirit of the invention.

30 In the drawings,—Figure 1 shows the invention in elevation; Fig. 2 is a transverse section; Fig. 3 is a section on the line 3—3 of Fig. 2, the sifter and ash pan appearing as added details. Fig. 4 is a section on the 35 line 4—4 of Fig. 2.

The stove comprises a casing, denoted generally by the numeral 1, the casing 1 including a top 2, a bottom 3, and walls, denoted by the numerals 4, 5, 6 and 7. Located within the casing 1, adjacent the wall 4, and rising from the bottom 3, is a primary baffle plate 8, having a lateral extension 9, constituting the bottom 10 of the upper oven 11, the ends of which extend to 45 the walls 6 and 7, the upper oven 11 comprising walls 12 and 14, and a top 15.

The invention further includes a secondary baffle plate 16, extended downwardly from the top 2, adjacent the wall 5 of the casing 1. The secondary baffle plate 16 is equipped with a lateral extension 17, located below and spaced from, the bottom 10 of the upper oven 11.

50 The lower oven, denoted generally by the numeral 11', is spaced from the wall 5, from the bottom 3, from the primary baffle plate

8, and from the extension 17 of the secondary baffle plate 16. The lower oven 11' comprises walls 18 and 19, a top 20, and a bottom 21.

60 The secondary baffle plate 16 and the wall 19 of the lower oven 11', together with the wall 5 of the casing 1, constitute a flue 22, communicating with the stack or stove pipe 23. In the secondary baffle plate 16, adjacent the top 2, and above the top 15 of the upper oven 11, there is a damper 24. In the extension 17 of the secondary baffle plate 16, to the rear of the wall 14 of the upper oven 11, and in vertical alinement with the 70 space existing between the wall 14 and the secondary baffle plate 16, is a damper 25. In alinement with the secondary baffle plate 16 and with the wall 19 of the lower oven 11', and controlling the space between the 75 top 20 of the lower oven 11' and the extension 17 of the secondary baffle plate, is a damper 26. Operating in alinement with the top 20 of the lower oven 11', and controlling the space between the wall 18 of 80 the lower oven 11' and the primary baffle plate 8, is a damper 27. It will be understood, without a specific description, that the several dampers above referred to, are accessible from the outside of the casing 1, 85 as is common in the art.

Access is had to the lower oven 11', by means of a door 29, access being had to the upper oven 11 by means of a door 28, the doors 28 and 29 being preferably, although 90 not necessarily, mounted for vertical swinging movement, and both doors being held in closed positions by means of a catch 30, of any desired construction.

95 The grate is denoted generally by the numeral 36, and may be of any desired form. This grate is supported by the wall 4 of the casing, and by the wall 12 of the upper oven 11. The grate 36 is positioned relatively near to the top 2 of the casing, as Fig. 2 will 100 clearly show. Located below the grate 36, carried by the wall 4 of the casing, and by the wall 12 of the upper oven 11, is a pair of guides 37, a similar pair of guides 38, being located below the guides 37. Slidably 105 mounted upon the guides 37, is a sifter, denoted by the numeral 39, and having a suitable face plate 40, constituting a closure for the opening in the casing, into which opening the sifter 39 is inserted. The guides 38 110 constitute a mounting for the ash pan 41, the same having a suitable face plate 42, as

clearly appearing in Fig. 1. The space 43 below the guides 38, constitutes an ash space, and access is had to this space 43, by means of a suitable door 44. To the wall 4 is 5 hinged a shelf 45.

In practical operation, presupposing that the parts are positioned as shown in Fig. 2, the operation of the device is as follows: The heated air and products of combustion, 10 generated above the grate 36 will pass, in the direction of the arrows, between the top 15 of the upper oven 11 and the top 2 of the casing 1. Thence, the products of combustion will pass between the wall 14 of the 15 upper oven 11 and the secondary baffle plate 16, thence between the bottom 10 of the upper oven 11 and the extension 17 of the baffle plate, thence between the baffle plate 8 and the wall 18 of the lower oven 11', 20 thence between the bottom 21 of the lower oven 11' and the bottom 3 of the casing 1, thence between the wall 19 of the lower oven 11' and the wall 5 of the casing 1, thence between the secondary baffle 16 and 25 the wall 5 of the casing, and thence into the stack or stove pipe 23.

When the circulation takes place as above described, it will be seen that both ovens will be maintained heated to a high degree. It is 30 possible, however, to cut out both ovens. In order to effect this result, the damper 24 is swung downwardly, permitting the products of combustion to pass from the space above the grate 36, directly into the stack 35 23. It is also possible, to heat the upper oven 11, without heating the lower oven 11' to the baking point. Under such circumstances, the damper 24 is closed, together with the dampers 25 and 27, the damper 26 40 being open. Under such circumstances, the products of combustion will pass across the top of the upper oven 11, along one side of the upper oven across the bottom of the upper oven, and thence between the extension 45 17 and the top 20 of the lower oven 11', into the flue 22, through the opening which is controlled by the damper 26.

Should it be desired to cut out the lower oven 11', and at the same time heat the upper oven 11, but to not so great a degree as 50 above described, the damper 24 may be closed, the dampers 25 and 26 being opened. Under such circumstances, the products of combustion, generated above the grate 36, 55 will pass along the top of the upper oven 11, along one side of the upper oven 11, and thence through the openings controlled by the dampers 25 and 26, into the flue 22, and thence into the stack 23.

From the foregoing it will be seen that it 60 is possible, by manipulating the dampers, to cut out both ovens, to cut out the lower oven, so to direct the products of combustion that the upper oven 11 will be heated on three sides, and so to conduct the products 65 of combustion that the upper oven 11 will be heated upon two sides only.

It will be understood readily, that the ashes from the grate 36 will be received by the sifter 39, and that the sifter 39 may be 70 reciprocated upon the guides 37, the minor portions of the ashes falling into the ash pan 41. If desired, the ash pan 41 may be removed, whereupon the ashes may be permitted to accumulate, to any desired extent, 75 in the space 43, from which space, the ashes may be removed through the door 44. Likewise, should the ash pan 41 overflow, such overflow will find its way into the space 43, thereby preventing a choking of the sifter 80 39 or of the grate 36.

Having thus described the invention, what is claimed is:—

In a device of the class described, a casing; spaced, superposed ovens therein; a 85 primary baffle plate rising from the bottom of the casing and having an extension connected with the upper oven; a secondary baffle plate depending from the top of the casing to one side of the upper oven and 90 having an extension protruding between the ovens, the secondary baffle plate defining a flue at the back of the casing; there being an opening in the secondary baffle plate above the upper oven and communicating 95 with the flue; there being an opening in the extension of the secondary baffle plate, aligned with the space between the upper oven and the secondary baffle plate; dampers for the openings; a damper positioned to control the 100 point of communication between the flue and the space between the lower oven and the extension of the secondary baffle plate; a damper positioned adjacent the top of the lower oven and adapted to open and to close the 105 space between the lower oven and the primary baffle plate; and a grate positioned between the ovens and one wall of the casing, upon the opposite side of the casing from the flue, the upper oven being spaced from 110 the top of the casing.

In testimony that I claim the foregoing as my own, I have hereto affixed my signature in the presence of two witnesses.

JOHN B. TURBEVILLE.
